A. WEBER.
TOOTH COMFORT KIT.
APPLICATION FILED APR. 11, 1918.

1,274,116.

Patented July 30, 1918.

UNITED STATES PATENT OFFICE

AUGUST WEBER, OF JERSEY CITY, NEW JERSEY.

TOOTH COMFORT KIT.

1,274,116.

Specification of Letters Patent.

Patented July 30, 1918.

Application filed April 11, 1918. Serial No. 227,948.

To all whom it may concern:

Be it known that I, AUGUST WEBER, a citizen of the United States, residing at Jersey City, in the county of Hudson and State 5 of New Jersey, have invented certain new and useful Improvements in Tooth Comfort Kits, of which the following is a specification.

My invention relates to a kit for receiving and holding a tooth brush and tube containing tooth paste.

An important object of the invention is to provide a kit of the above mentioned character, which is small, compact, inexpensive to manufacture, and convenient in use.

Other objects and advantages of the invention will be apparent during the course of the following description.

20 In the accompanying drawings forming a part of this specification and in which like numerals are employed to designate like parts throughout the same,

Figure 1 is a side elevation of a kit embodying the invention,

Fig. 2 is a similar view, the outer casing being shown in longitudinal section,

Fig. 3 is a central vertical longitudinal sectional view through the entire device,

30 Fig. 4 is a plan view of the device, the outer casing being shown in longitudinal section,

Fig. 5 is a side elevation of the tooth brush removed, and,

35 Fig. 6 is a transverse sectional view taken on line 6—6 of Fig. 1.

In the drawings, wherein for the purpose of illustration is shown a preferred embodiment of my invention, the numeral 10 designates an inner casing constituting the body portion of the kit or device. This inner casing is provided upon one side with a main longitudinal opening 11, as clearly shown in Fig. 4. The forward end of the 40 inner casing 10 is provided with a tapered head 12, having a central opening 13. The rear end of the inner casing 12 is covered by a removable cap 14, having screw-threaded engagement therewith, as shown at 15.

45 Arranged within the inner casing 10 is a flexible tube 16, preferably formed of rubber, and having an opening 17 formed in its forward end. A tube 18, containing tooth paste, is inserted within the flexible 50 tube 16, and the cap 19 of the tube 18 extends through the openings 13 and 17, and

projects forwardly beyond the same for a slight distance, whereby it may be conveniently turned. It is obvious that by application of pressure upon the flexible 60 tube 16, at the opening 11, the tooth paste may be discharged from the tube 18, the cap 19 having been removed.

The numeral 20 designates a tooth brush as a whole, comprising a back 21, carrying 65 the bristles 22. The back 21 is secured to a handle 23. The handle 23 is provided at its forward end with a reduced portion 24, forming a shoulder 25, and at its rear end with a head 26, having outer and inner extensions 27 and 28, as shown. The head 26 projects outwardly beyond the handle 23, forming a shoulder 29, as shown.

The forward end of the inner casing 10 is provided with a recess or notch 30, receiving the reduced portion 24 of the brush, the shoulder 25 contacting with the wall of the head 26. At its rear end, the inner casing 11 is provided with a transverse opening 31, for the reception of the head 26. The outer extension 27 of the head extends across the outer face of the screw-threaded portion 15 of the inner casing 10, but has no screw-threaded engagement therewith, while the inner extension 28 projects inwardly of the 85 same, as clearly shown in Fig. 4.

The cap 14 is provided with an opening or notch 32 adapted for the reception of the extension 27. It is thus apparent that when the extension 27 projects into the opening or 90 notch 32 the cap 14 is locked against turning movement.

The numeral 33 designates an outer casing having its forward end closed while its rear end is formed open and adapted for 95 insertion over the inner casing 10, the same having a suitable sliding fit. The rear end of the outer casing 33 is adapted to contact with the forward end of the cap 14, and this rear end is provided with an opening or notch 35, for the reception of the forward portion of the head 26, the shoulder 29 contacting with the end wall of the opening 25. As shown in Fig. 1, the outer surface of the head 26 and the surfaces of the cap 14 and 100 casing 33 are flush.

In the use of the kit, with the elements thereof assembled as shown in Fig. 4, when it is desired to remove the tooth brush, the outer casing 33 is first removed from the 110 inner casing 10, by a longitudinal movement of the outer casing with relation to

the inner casing. The brush 20 may then be separated from the inner casing by a similar movement, thus uncovering the opening 11. The brush 20 may then be held 5 in the hand in the usual manner and pressure applied through the opening 10 upon the flexible tube 16 and tooth paste tube 18 contained therein, whereby the tooth paste will be discharged from the tube, the cap 10 19 being removed. It is obvious that the opposite of this operation takes place in assembling the several elements of the kit. When it is desired to remove the tooth paste tube 18, the outer casing 33 and tooth brush 15 are first removed whereby the cap 14 may be unscrewed. Particular attention is called to the fact that when the tooth brush is in the assembled position and the outer casing 33 in place, the cap 14 is locked against turning or unscrewing movement.

It is to be understood that the form of my invention herewith shown and described is to be taken as a preferred example of the same, and that various changes in the shape, 25 size, and arrangement of parts may be resorted to without departing from the spirit of the invention or the scope of the subjoined claims.

Having thus described my invention, I 30 claim:

1. In a kit of the character described, an inner tubular casing provided with a main longitudinal opening and a transverse opening at one end of the main longitudinal opening, said inner tubular casing being provided 35 at the opposite end of the main longitudinal opening with a notch; a tooth brush having a handle provided at one end with a reduced portion to fit within the notch and at its opposite end with a head to fit within the 40 transverse opening and carrying outer and inner extensions to be arranged upon opposite sides of the wall of the inner tubular casing; a cap having screw-threaded engagement with the rear end of the inner tubular 45 casing and provided with a recess to receive the outer extension; and an outer tubular casing adapted to be passed about the inner

tubular casing and brush and provided at its rear end with the recess to receive a portion 50 of said head.

2. In a kit of the character described, an inner tubular casing adapted for the reception of a tooth paste tube, a cap having screw-threaded engagement with one end 55 of the inner tubular casing and provided with a recess, a tooth brush having a handle extending longitudinally of the inner tubular casing with a portion of the handle projecting into the recess of the cap, and an outer 60 tubular casing to receive the brush and inner tubular casing.

3. In a kit of the character described, an inner tubular casing having a main longitudinal opening and provided at its forward end with a head having a contracted opening, a flexible tubular casing arranged 65 within the inner tubular casing and provided at its forward end with a contracted opening in registration with the first named contracted opening, a tooth paste tube arranged within the flexible tubular casing and having its cap extending through and beyond the contracted openings, a cap having screw-threaded engagement with the rear end of 70 the inner tubular casing, a tooth brush having a handle having interlocking engagement with the inner tubular casing and its cap, and an outer tubular casing receiving the 75 brush and inner tubular casing.

4. In a kit of the character described, a tubular casing adapted for the reception of a tube of tooth paste, a tooth brush having a handle extending longitudinally of the tubular casing, means for effecting a locking engagement between the handle and the tubular casing, a cap having screw-threaded engagement with one end of the tubular casing, and means for effecting a locking engagement between the cap and handle whereby 85 the cap cannot rotate with respect to the tubular casing when the handle is in the active position.

In testimony whereof, I affix my signature, this 6th day of April, 1918.

AUGUST WEBER.
